Application February 26, 1936, Serial No. 65,865
In Germany December 10, 1934

12 Claims. (Cl. 132—79)

This invention relates to a container adapted for instance for cosmetics like perfume, face powder, soap, or for keeping therein chalk, colophony, colored pencils, etc.

5. The containers hitherto used for keeping articles of the kind mentioned were provided with covers, and it was therefore necessary to employ both hands to open the container and remove a portion of its contents. This method is quite 10 bothersome and, furthermore, open to the objection that during the removal of a portion of the contents parts thereof dropped over the edge of the container and frequently soiled other articles.

10. The invention eliminates these drawbacks by 15 providing a container which can be opened and closed with one hand and which when opened fully exposes the article kept therein. The container preferably comprises a casing and folding means acting upon the casing so as to place it around the object during closing of the container. Levers or other suitable means may be provided 20 for winding the encasing material around the object, and the construction may be such that the levers or other means are for instance jointly 25 brought by hand into opening position against the action of a spring.

According to the invention, the container can be particularly advantageously constructed in the 30 form of a flower whose petals constitute the walls of the container and can be turned up or down. In opened position the petals form a protective 35 guard for catching portions of the contents, such as powder particles, dropping out of the container. The inside of the flower serves for holding a perfume receptacle, a powder box with puff, etc., and one of the petals may be constructed so as to have a mirror on its inside. The petals are carried by a plate or by closing levers articulated to the calyx and passing into closing position by spring 40 action, whereas the drive for the levers comprises a springy pressing plate arranged in a handle and connected at its ends with the closing levers by means of a drawing device, or the closing levers are provided with drawing means passing through 45 the calyx and, on being actuated, bringing the petals into opening position.

It is further possible to construct a flower-like container so that perfume is emitted by a receptacle disposed in the blossom when the actuating 50 device is depressed.

By way of example, several embodiments of the invention are illustrated in the accompanying drawings, in which Figure 1 is a section of the closed container; Fig. 2, a section of the opened 55 container; Fig. 3, a bottom view of Fig. 1; Fig. 4,

a view of a container constructed in the form of a flower; Fig. 5, a section of Fig. 4; Fig. 6, a section of the opened container according to Fig. 4; Fig. 7, a section of another form of container; Fig. 8, a section of the opened container according to Fig. 5; Fig. 9, a section of still another form of container; Fig. 10, a detail view of Figs. 7 to 9; and Fig. 11, a partial top view of the driving mechanism for the container shown in Figs. 4 to 6.

Referring to the drawings, 1 is a piece of colophony, chalk, etc. which in the embodiment shown in Figs. 1 to 3 is covered by a cloth 2 and pasted or glued thereto with its bottom. The cloth 2 and the article 1 are firmly arranged on a carrying plate 3 of the holding device which on its underside is fitted with the bearings 4 for the levers 5 which embrace the article 1 and whose ends are suitably connected with the cloth 2. The levers 5 are disposed on the journals 6 and bent back below the plate 3 to form the eye 7, as shown in Figs. 1 and 2. This eye 7 is provided with a rigid ring 8 the diameter of which is somewhat larger than the distance between the opposite bearings 4 and which possesses the handle 9. 10 are springs placed around the journals 6 and having the tendency to bring the levers 5 into closing position.

The device functions as follows:

When the holding device is in the position according to Fig. 1, the article 1 will be fully covered by the cloth 2. If the article, such as colophony, is to be used, the forefinger and the middle finger of one hand grasp the two handles 9 of the ring 8. By exerting pressure with the thumb on the plate 3 the latter is lifted off from the ring 8, so that, owing to lever action, the levers 5 are brought into opening position, as indicated in Fig. 2, against the action of the spring 10. The cloth 2 is now spread apart and catches the colophony dust produced for instance by passing the colophony over the strings of a bow.

In the construction according to Figs. 4 to 6 and 11 the container serves as powder box and has the shape of a flower, such as a rose. The petals 11 are arranged on the closing levers 12 which, as shown in Fig. 11, are movably disposed on the shafts 13 in the calyx 14 provided with a guide 15 which is open also below and through which chains, cords, etc. 16 united to form a drawing device are passed.

Below each bearing of a closing lever 12 the calyx 14 possesses an opening 17 for passing the drawing means 16 to the outside where it is actuated. The spring 18 on the shaft 13 tends always to place the closing levers 12 into closing 55

position. By pulling the drawing means 16 the closing levers 12 are moved outwardly in the direction of the arrow shown in Fig. 5, so that the petals 11 are spread. During the spreading motion of the petals 11 the powder box 20 with its puff 21 carried on the calyx 14 by the holders 19 is exposed, and the device is ready for use. When the drawing means 16 are released, the petals 11, owing to the action of the springs 18, pass again into closing position according to Fig. 4.

The construction according to Figs. 7 to 10 shows a container also intended for keeping face powder, face paint, perfume, etc., and provided with a carrying plate 22 serving also as receptacle for the powder 23. 24 is the puff. On the underside of the carrying plate 22 a handle 25 is provided having on both sides elastic pressing plates 26. On the shafts 13' arranged on the carrying plate 22 the closing levers 12' are disposed and surrounded by the petals 11', as indicated in Fig. 10. Approximately in the center of the carrying plate 22 the tension springs 27 are arranged which in the manner indicated in Fig. 10 pass over the shaft 13' and engage the closing levers 12' so as to draw them into closing position. The shaft 13' has further wound thereon the draw chain 28 which is connected with the ends of the pressing plate 26, as shown in Fig. 7. If the plates 26 are pressed out of the position shown in Fig. 7 and into the position according to Fig. 8, the chains 28 will unwind from the shafts 13' which are turned so that the closing levers 12' with the petals 11' move outwardly and expose the powder box.

The carrying plate 22 may further be provided with the stamens 29, and the handle 25, as shown in Fig. 9, may contain a perfume receptacle 30 formed of rubber or other suitable material, which during compression of the plates 26 is compressed also to emit perfume through the opening 31 while, simultaneously, the flower opens.

Instead of the closing and opening means described other suitable devices can be employed, and the container may serve for keeping all sorts of material besides those mentioned without departing from the scope of the invention.

I claim:—

1. A container, comprising a casing forming the walls thereof and surrounding the object contained therein on all sides and means constructed as carrying handle for the container and adapted to be operated by one hand for opening and closing said casing, said casing when in open position forming a protective guard for catching portions of the contents dropping out of the container.

2. A container according to claim 1, wherein the casing is formed of a plurality of parts, comprising supporting means for the contents, levers for supporting the parts of the casing and articulated to said supporting means and a joint control member for all levers, said control member forming the carrying handle.

3. In a container according to claim 1 springs for placing the casing in closing position wherein the contents are embraced on all sides by the casing.

4. A container, comprising supporting means for the contents, parts shaped like petals and arranged on said supporting means to form a casing for the contents, an actuating device for the petals formed as calyx and operable by one hand, said device serving also as handle for the container, and springs for returning the petals to closing position.

5. A container according to claim 4, wherein the supporting means for the contents is constructed as calyx of a flower.

6. In a container according to claim 4 a perfume receptacle on the supporting means.

7. In a container according to claim 4 a powder box with puff on the supporting means.

8. A container according to claim 4, wherein the actuating device for the petals is constructed as stem and calyx of the flower.

9. In a container according to claim 4 a perfume receptacle on the supporting means, said receptacle extending into the actuating device 35 and emitting a predetermined quantity of perfume when the petals are opened.

10. A container, comprising supporting means for the contents constructed as the lower portion of a flower, petals articulated to the supporting means, closing levers for carrying the petals and embracing the contents, springs for bringing the closing levers into closing position, an actuating device forming the calyx of the flower and serving also as handle and means for connecting the closing levers with the actuating device.

11. In a container according to claim 10 pressing plates forming the actuating device and drawing devices forming the connecting means.

12. A container according to claim 10, wherein one of the petals is constructed as mirror on its inside.

JOACHIM SIEGERT.
